UNITED STATES PATENT OFFICE.

MORRIS G. ROSENTHAL, OF CINCINNATI, OHIO, ASSIGNOR OF ONE-HALF TO FRED E. KLEIN, OF CINCINNATI, OHIO.

TAG-MOUNTING MACHINE.

Application filed March 4, 1922. Serial No. 540,956.

To all whom it may concern:

Be it known that I, MORRIS G. ROSENTHAL, a citizen of the United States, and a resident of Cincinnati, in the county of Hamilton and State of Ohio, have invented certain new and useful Improvements in Tag-Mounting Machines, of which the following is a full, clear, and exact description, reference being had to the accompanying drawings, forming part of this specification.

My invention relates in its special application to devices for stitching tags to articles of laundry for the purpose of identifying them, said tags to be sewed on with a stitch that will pull out, so as to permit removal of the tag.

The development of this machine has as its objects various features, some of which have application to sewing machines in general, and some to tag feeding devices and the like.

Thus it is my object to provide a stop motion for sewing machines, which operates to stop the operation of the machine by first shutting off the motive power and then permitting the parts to run of their own momentum for certain revolutions or parts of revolutions, after which they are positively stopped.

It is my object to provide a mechanism which will control the number of stitches made by the needle, which by the substitution of different toothed pinions and cams, can give any desired number of stitches prior to the stop and any desired momentum revolutions.

It is my object to provide in connection with the machine a thread cutter which will be of positive operation and will give a length of thread free for ready accessibility in pulling out the stitches.

It is also my object to provide a feed device for rigid or semi-rigid individual tags, which will feed a tag into the stitching parts of the machine and then release it sufficiently to permit the fabric feed of the machine to draw it along with the fabric to which the tag is being stitched.

The holder for marking tags is especially designed to receive the metal and fabric hanger tags, of the type shown in my ap-

plication for patent filed December 31, 1921, Serial No. 526,171.

In connection with the timed stop motion device, it is my object to provide for a simple and effective resilient bumper action, secure against back lash and capable of locating the fly wheel and shafting of the machine so that the needle is always elevated when the machine is stopped.

I have not attempted to modify the action of the sewing machine proper and have not shown in detail the kind of machine used, since any draw thread machine would be proper for use. In the broader aspects of my invention, either lock or chain stitch machines could be used, the reason for using a draw thread in the tag mounting machine being because I desire to permit removal of the tag by pulling out the thread or threads of the stitches.

The above objects and other advantages to be noted I accomplish by that certain construction and arrangement of parts to be hereinafter more specifically pointed out and claimed.

In the drawings,

Figure 1 is a front elevation of the machine complete except for the starting pedal.

Figure 2 is a detail side elevation of the timing members of the stop motion.

Figure 3 is a detail end elevation with certain parts removed, showing the machine shaft stopping elements.

Figure 4 is a detail end elevation showing the connections between the starting pedal and the presser foot arm.

Figure 5 is a detail plan view showing the presser foot, tag holder and tag feed, with the upstanding parts in section, as taken on the line 5-5 of Figure 1.

Figure 6 is a view on a larger scale, showing in rear elevation the tag mounting device.

Figure 7 is a perspective view of the tag mounting device.

Figure 8 is a side elevation of the thread cutter, showing the work table of the machine in section.

The sewing machine, having a work table 1, needle 2 and frame 3, is merely indicated in the drawings as showing any familiar

type of sewing machine. There is also shown the fly wheel 4, to which is attached the driving pulley 5, said fly wheel being on the main shaft 5^a of the machine, and the drive for the pulley 5 being ordinarily by means of a belt from an individual electric motor (not shown). I have diagrammatically shown a foot pedal 6 connected to a pull rod 7 and having also thereon a bar 8, which operates a switch enclosed in a cabinet 9.

Pivoted to the frame of the machine is a rocking bar 10, its pivot being on a stud 11. In this bar is slidably held a spring bumper post 12. On a pin 13, extending from the top of the rocking bar a frame 14 is journaled. This frame is constructed substantially as shown in Figures 1 and 3, with the back portion extended to form a latch 15 with a beveled engagement face 16. A torsion spring 17, bearing against the upper portion of the frame is wound around the pin 13, with one end retained by the rocking bar. The other end is attached to the frame 18 so that the frame is resiliently held by the spring in a horizontal rotative position against a bar 18 extended from the rocking arm. This bar engages the top part of the pin 13 and a tension spring 19 with one end abutting the bar 18 and the other abutting the frame which presses downwardly against the small frame.

On the shaft 5^a is an arm 20 having a beveled end, which, as the shaft revolves, will first strike the beveled face 16 of the hook latch 15, so as to swing the frame out of the way. The arm 20 will then strike the spring bumper post and be brought to a stop, while as soon as the post is struck by the arm, the frame will be permitted to swing to its original position, bringing the hook over the arm and thereby providing a resilient take-up for any rebound and holding the shaft arm at a predetermined position, which, as stated, will leave the needle elevated, ready for another operation.

The bar 10 has two teeth on its lower end, the tooth 21 and the tooth 22. The former tooth is engaged by a pawl 23 pivoted at 24 on the machine frame, and connected to the pull rod 7 of the foot pedal 6. The tooth 22 is adapted to be engaged by the shoulder 25 on a rocker arm 26 pivoted at 27 on the machine frame. The bar 10 is pulled by a spring 27^a toward a position with the latch 15 and the bumper post 12 in alignment with the arm on the machine shaft. When in such position, the tooth 21 at the lower end of the bar contacts with another shoulder 28 on the rocker 26. The pawl 23 is spring pulled at 28^a to a position ready for engagement with the tooth 21 of the bar.

As so constructed, the operation of pressing down on the pedal rocks the pawl 23 and moves the lower end of the bar 10 so as to

swing the latch and bumper post out of position to block the operation of the machine. The tooth 21 which engages the pawl as long as the bar 10 is in an approximate vertical position disengages the driving edge of the pawl at the point of extreme throw of the pawl as moved by the foot pedal 6. To hold the rocker 10 in position when the pawl is no longer in cooperative position with the tooth 21, the tooth 22 strikes against the shoulder 25 on the rocker bar and thus holds the arm 10 in this position. The shoulder 25 holds the arm 10 in position until the machine shaft causes the rocker arm to be rocked up at the end opposite the shoulder so that the shoulder disengages the tooth 22 and the arm 10 is pulled by the spring 27^a back to the vertical engaging position. The foot pedal as soon as it is released is pulled up by a spring which will be hereinafter described and the pawl moves back to the starting position with its edge in position to engage the tooth 21.

Upon a movement of the rocker, the bar 10 will be freed to move under impulse of its spring into shaft blocking position, and the pawl 23 will be free of the bar and its teeth until the rheostat switch is released, when the pawl will come into engagement with the tooth 21, ready to operate the bar for another operation of the machine.

The pedal will either have its own spring or will be pulled by the spring on the pawl 23 into elevated position when it is released, thereby turning off the current from the driving motor through the medium of the switch. The pedal will have to be held down throughout the major part of the motion of the machine.

I also provide for an additional switch for the current to the motor, which is controlled from a timing device connected to the moving parts of the sewing machine.

Thus I show as an exemplary form, a terminal 30, to which is connected a resilient metal conductor strip 31. The other end of this strip is connected to a link 32, which is pivoted to the rocker 26 and a slight movement of the rocker not sufficient to release the stop bar 10, will move the strip 31, so that it does not maintain a contact with the other electric terminal 32^a. By this means, a partial movement of the rocker will cut off the flow of current to the motor and the machine parts are still free to fly around of their own momentum until a further movement is applied to the rocker to entirely release the bar 10.

On a shaft 33, which operates the lower thread parts of the sewing machine and the work feed and which is connected to the main shaft by suitable means, is a collar 34 positioned by a set screw on the shaft and having a lateral pin 35 near its periphery.

Located above this collar is a star wheel or pinion 36, the teeth of which the pin engages, so that at each revolution of the shaft 33, which is timed to be equal to the cycles of movement of the needle, the star wheel is given a movement of one tooth.

On the star wheel is a cam 37 against which rests the rod 38 connected to the rocker 26. A spring 39 around the rod 10 holds the rocker in position with the rod thereon against the cam, and incidentally the shouldered outer end in position to spring into engagement with the bar 10 and also the switch plate in position to maintain 15 an electric contact.

The cam has its periphery arranged with a surface 40, which will hold the rocker in position to pull the switch strip out of contact, and a high nose 41 which will release 20 the rocker from engagement with the bar 10.

I preferably arrange the parts so that the portion 40 of the cam will hold the switch out for about two revolutions of the fly wheel and main shaft, after the current has 25 been shut off.

The advantages of this form of stop motion are obvious, as they free the motor and the parts of the sewing machine from jar incident upon stopping the mechanism.

30 The presser foot 39^a of the machine is connected by a rocker arm 40^a with a link 41^a. This link 41^a is attached to a lever 42 which is coupled to the pull rod of the foot pedal, and a spring 43 attached between the 35 frame and the lever exerts a tension to pull down on the link 41^a and raise the presser foot so that the work will be free to move under the needle, as in any sewing machine. When the foot pedal is depressed to start 40 the motor and release the main shaft of the machine, the presser foot will be released, so that the work will be clamped down beneath the foot. When the machine stops and the lever 42 is not interfered with, the 45 spring 43 pulls the lever so as to raise the presser foot, overcoming the force of the normal spring of the presser foot.

The tag holder is constructed as follows: A three-sided rectangular box 44 is provided 50 of the cross section equal approximately to the size of a tag. In this box are a pair of pins 45 having their upper and lower ends pointed as at 46. The tags, as shown, have body portions 47 in which are holes 48 having narrow slits 49 extending from the holes to the backs of the tags. The fronts of the tags may be made up of a flexible loop of fabric 50. The slits in the backs of the holes will slide over the pointed ends of the pins, 55 but the act of moving the tags along the pins from the ends will result in the large parts of the pins filling the holes and retaining the tag slidably but irremovably.

60 A small platform 51 is erected on the work table of the machine to the right of

the needle, this platform having an overhanging lip or tongue 52 and a short stud 53. The box 44 is formed with flanges at its lower end, one of which, as at 54, is adapted to be inserted under the tongue and the 70 other of which, as at 55, has a hole therein to engage over the stud. A latch 56, mounted alongside the platform, swings over this flange 55, thereby holding the box down firmly with the stud acting as a locating 75 member.

Hung on a suspended link 57 is a tongue 58 which, when the link is swung, will pass through a slot 59 in the back wall of the 80 box at the base thereof.

The box, when seated on the platform, acts to push the two pins into a position so that the pointed ends are within the inside of the box, so that the lowermost tag can slip out of the open front of the box. The 85 link is swung so as to insert the tongue through its slot and push the lowermost tag forward to a position beneath the presser foot.

In mounting the tags in the box it is 90 removed from the platform, whereupon the two pins will fall until the pointed ends at the top are within the box, whereupon the box can be filled with tags inserted from above and dropped down over the pins.

To serve as a lateral guide in the feeding of the tags, the platform is formed with a shoulder 60 from which extends a pin 60^a, which lies above the platform, said platform having a slight slope at this point. On the other side of the platform is a rocking arm 61 mounted on a stud and bracket 62 and having a spring-pressed end 63, the other side of the stud. A finger 64 extends inwardly from the presser foot and engages the spring-pressed end of the arm, so that when the presser foot is raised, as it is when the tags are fed, the arm lies along the platform and forms the other side guide. When the machine is working and the foot is down, the finger 64 will raise the arm, thereby permitting the tag to feed along with the fabric to which it is being stitched.

Starting with the presser foot up and the machine idle, the operator inserts a piece of 115 fabric to be marked beneath the presser foot and under the needle. He then throws over the arm 57, which forces a tag out of the box, since the pins in the box will have been thrust upwardly in mounting the box, thereby bringing the thin ends of the two tag retaining pins up into the box and freeing the lowermost tag for sliding outwardly.

The tag moves to a position lying directly 125 beneath the needle over the fabric to be marked, the tongue 58 having a limited movement determined by the link 57 striking the box or any other stop desired.

The operator then presses down on the foot 130 pedal which pulls over the stop device to

free the main shaft of the machine, and at the same time electrically connects in the motor through the box 9 (preferably a rheostat switch).

5 When the arm 10 is swung over the rocker 26 is free to move under influence of the spring 39, thereby keeping the circuit to the motor at 32^a closed. Also upon depression of the pedal the presser foot comes down, 10 clamping the fabric end of the tag to the fabric, and the machine starts to stitch the tag to the fabric with a chain stitch.

The presser foot has freed the tag so that it can move along with the fabric under 15 influence of the usual work feed in the machine by rocking down the rear end 63 of the guide member 61.

The needle will move up and down for the 20 desired number of motions, say, four, where- upon the devices beneath the table coupled up with the lower needle shaft will make the first movement that cuts off the current at 32^a without releasing the arm 10 with the 25 catch and bumper post in position to block the arm 20 on the needle driving shaft. The motor and sewing machine parts will continue to move because of the kinetic energy remaining in them, for say, two more motions of the needle, whereupon the rocker 26 30 will complete its movement, thereby releasing the stop device and bringing the machine operating parts to a full stop, with the needle elevated. Upon the release of the foot pedal as noted the presser foot moves to the elevated position.

35 The operator then withdraws the fabric and tag, and cuts off the thread, by means of a special mechanism which I will now describe.

40 This mechanism comprises a knife 70 mounted in a slot in the table 1 of the machine. A guard 71 is provided which is screwed down to the table over the slot as 45 illustrated at 72, and has a slot 73 therein lying over the knife. Due to a slight inclination in the guard, the knife lies in the slot for a part of its length, but the knife is turned down at 74, and the guard turned up at 75, permitting the easy introduction of 50 the thread between knife and guard by the operator.

55 As the operator pulls the fabric and tag to bring the thread under the guard and draws the fabric toward him, the thread is caught between the guard and knife and pressed against the knife by the guard, so that it is easily sheared as it is pulled along the knife edge.

60 The machine is then ready for another operation with the parts all at rest and everything reset for another operation. The spring 57^a pulls back the tag feed tongue, as will be evident, and the return of all other parts has already been noted.

65 I do not desire to be limited in the claims

that follow to the particular mechanical expedients set forth in the above description, merely because of my failure to mention the possibility of substitution of equivalents as the description proceeded.

70 Having thus described my invention, what I claim as new and desire to secure by Letters Patent, is:—

1. In a sewing machine, the combination with driving means adapted for connection with a source of electric power, a stop for the driving means, a switch controlled by the driving means, a switch controlled by the operator, both of said switches in circuit with the electric source of power, a release for the stop, and connections from the first named switch to the stop, and from the second named switch to the stop release, for the purpose described.

75 2. A stop motion for sewing machines or the like, comprising a member operated by the machine, an electric switch operated by said member for cutting off motive power from the machine, a stop controlled by the member for stopping the machine, said member adapted to operate first the switch to break electric connection, and then permitting one or more revolutions of the machine, and finally operating the stop.

80 3. A stop motion for sewing machines or the like comprising a member operated by the machine, an electric switch operated by said member for cutting off motive power from the machine, a stop controlled by the member for stopping the machine, said member adapted to operate first the switch to break electric connection, and then permitting one or more revolutions of the machine, and finally operating the stop, and a member 85 to release the stop, and a switch operated by said member to supply electric current to the machine.

100 4. A stop motion for sewing machines or the like, comprising a member operated by the machine, and having a step-by-step motion, a switch for supplying current to the machine operated by the first step of the motion of said member, and a stop for the machine operated by the next step of the motion of said member.

105 5. A stop motion for sewing machines or the like, comprising a member operated by the machine, and having a step-by-step motion, a switch for supplying current to the machine operated by the first step of the motion of said member, and a stop for the machine operated by the next step of the motion of said member, and a starting device for the machine adapted to release said stop and simultaneously accomplish a resetting of said member to position of closing its switch.

110 6. A stop motion for sewing machines or the like, comprising a member operated by the machine, and having a step-by-step mo-

tion, a switch for supplying current to the machine operated by the first step of the motion of said member, and a stop for the machine operated by the next step of the motion of said member, and a starting device for the machine adapted to release said stop and simultaneously accomplish a resetting of said member to position of closing its switch, said starting device comprising a 10 rheostat starting switch.

7. A stop motion for sewing machines or the like, comprising a toothed member operated step by step with the machine, a stop for the machine, a switch for the machine, and means as a cam and a lever operated by said cam and adapted to first release the switch and next to release the stop.

8. In a sewing machine or the like, a stop member for the machine adapted to be resiliently held toward machine stopping position, an operable element for positively moving said stop to machine releasing position, a latch for holding it in machine releasing position, a switch controlled by said 20 latch for supplying power to the machine and adapted to open upon partial movement of the latch, and automatic means to move the latch to switch opening position, then holding it, and finally moving it to stop 25 releasing position.

9. In a sewing machine or the like, a stop member for the machine adapted to be resiliently held toward machine stopping position, an operable element for positively 30 moving said stop to machine releasing position, a latch for holding it in machine releasing position, a switch controlled by said latch for supplying power to the machine

and adapted to open upon partial movement of the latch, and automatic means to move the latch to switch opening position, then holding it, and finally moving it to stop releasing position, said latch adapted to return to switch closing position upon operation of the stop by the operable element. 40

10. In a sewing machine or the like, means for starting the machine by application of power and operation of a stop to releasing position, and means controlled by the machine for cutting off power therefrom, holding the power off for one or more revolutions of the machine, whereby it operates by kinetic energy, and then accomplishing of movement of the stop to machine stopping position. 50

11. In a machine of the character described, means for stopping the operation thereof, comprising a carrier, a bumper stop on the carrier, a return motion stop on the carrier, and means for moving the carrier to a position to bring the bumper in the path of a moving machine part, said return motion stop comprising a resilient part adapted to latch automatically over the said moving part. 60

12. In a machine of the character described, means for stopping the operation thereof, comprising a rocking bar, a resiliently mounted bumper stop on said bar, and frame resiliently sliding on the bar, torsion spring means acting on said frame, and a hook on the frame adapted to snap past and over a moving part of the machine prior to its contact with the bumper. 70

MORRIS G. ROSENTHAL.
